CLAIM

The ornamental design for wall loudspeaker mounting system, as shown and described.

DESCRIPTION

FIG. 1 is a front bottom perspective view of a loudspeaker mounted on an on-wall speaker mounting system.

FIG. 2 is a rear top perspective view of the on-wall speaker mounting system.

FIG. 3 is a front right side perspective view of the on-wall speaker mounting system.

FIG. 4 is a rear right side perspective view of the on-wall speaker mounting system.

FIG. 5 is a right side elevation view of the on-wall speaker mounting system.

FIG. 6 is a left side elevation view of the on-wall speaker mounting system.

FIG. 7 is a bottom elevation view of the on-wall speaker mounting system.

FIG. 8 is top elevation view of the on-wall speaker mounting system.

FIG. 9 is a front elevation view of the on-wall speaker mounting system.

FIG. 10 is a rear elevation view of the on-wall speaker mounting system; and,

FIG. 11 is a front top perspective view of the wall loudspeaker mounting system with the shell of the wall fastening portion removed to view the internal structure shown in broken lines that form no part of the claimed design.

The broken line depict environments that forms no part of the claimed design.
